UNITED STATES PATENT OFFICE.

FREDERICK E. KEY, OF ST. LOUIS, MISSOURI, ASSIGNOR TO KEY BOILER EQUIPMENT COMPANY, OF ST. LOUIS, MISSOURI, A CORPORATION OF MISSOURI.

GRAPPLING DEVICE.

1,318,087.

Specification of Letters Patent.

Patented Oct. 7, 1919.

Application filed May 27, 1918. Serial No. 236,911.

To all whom it may concern:

Be it known that I, FREDERICK E. KEY, a citizen of the United States of America, a resident of the city of St. Louis, State of Missouri, have invented certain new and useful Improvements in Grappling Devices, of which the following is a full, clear, and exact description, reference being had to the accompanying drawing, forming a part of this specification.

My invention relates to improvements in grappling devices, one of the objects being to produce a simple and efficient device of this kind which can be very easily and quickly attached to and removed from the object to be secured.

More specifically stated, an object is to produce an improved grappling device for securing tubular articles having circular openings. The new device preferably comprises a plurality of clutch members adapted to be inserted into and interlocked with the object to be secured. One of the clutch members is preferably pivoted to the others, and this pivoted member can be turned on its axis to allow the device to be inserted into, interlocked with, or removed from a hollow object. A spring is preferably associated with the pivoted clutch member so as to automatically move said pivoted member to its attaching position wherein it interlocks with the object to be secured.

With the foregoing and other objects in view the invention comprises the novel construction, combination and arrangement of parts hereinafter more specifically described and illustrated in the accompanying drawings wherein is shown the preferred embodiment of the invention; however, it is to be understood that the invention comprehends changes, variations and modifications which come within the scope of the claims hereunto appended.

Figure I illustrates the grappling device as used in applying plugs to a steam boiler, the elements of the boiler being shown in section and the grappling device being shown in elevation.

Fig. II is an enlarged top or plan view, illustrating the grappling device applied to a tapered plug.

Fig. III is a side elevation, partly in sec-

tion, showing the grappling device arranged within the tapered plug.

Fig. IV is a side elevation of the grappling device looking in the direction indicated by the arrow IV, Fig. II.

The grappling device herein shown can be conveniently used for the purpose of attaching hollow boiler plugs to a flexible lifting device whereby the plugs are elevated and drawn into the openings to be closed. I am aware that the device can be used for various other purposes, and it is to be understood that the invention is not limited to a device for lifting objects having tapered openings.

The boiler herein shown in Fig. I is provided with hand holes 1 to be closed by hollow tapered plugs A, which are primarily inserted through a relatively large opening 2 near the bottom of the boiler.

The grappling device is suspended from a chain 3, and it preferably comprises a pair of rigid sheet metal clutch wings 4 formed integral with each other and arranged at an angle to each other, as shown most clearly in Fig. II. The sheet of metal is deflected to form the diverging wings 4, and it is preferably punched to provide a pair of pivot-receiving ears 5 and 6. A pivot 7, preferably an ordinary cotter pin, passes through the ears 5 and 6. 8 designates a clutch wing having pivot-receiving extensions which lie between the ears 5 and 6 (Fig. IV), said wing 8 being pivotally supported by the pin 7. A spring 9, coiled around the pivot pin 7, has an extended end 10 which engages the pivoted clutch wing 8 and an extended end 11 engaging one of the wings 4. This spring 9 is under tension and it normally retains the clutch wing 8 in engagement with a stop member 12 (Figs. II and IV) projecting from the ear 5.

The pivot 7 is eccentric relative to the center of the circular opening in the cap A, but the axis of the pivot is parallel with the axis of the circular member A. The clutch wing 8, moving about the axis of the pivot, can therefore be shifted to the position shown by dot and dash lines in Fig. II. When the clutch wing 8 occupies the last mentioned position, the grappling device can be inserted into or removed from the ta-

pered opening in the hollow plug A. This clutch wing 8 can be very easily moved by hand, and when released it will be thrown by the spring 9 to the position shown by 5 full lines in Fig. II.

The outer edges of the clutch wings are preferably inclined as shown at X in Figs. III and IV, so as to conform approximately to the inclination of the tapered inner face 10 of the hollow plug A. When the device is in its expanded condition, *i. e.*, when the pivoted wing 8 is extended as shown by full lines in Fig. II, the inclined edges X of the clutch wings lie very close to the inner face 15 of the hollow tapered plug. The grappling device is then interlocked with, or attached to, the tapered plug A, and it cannot be withdrawn while the clutch wing 8 occupies the position shown by full lines in Fig. II.

20 However, the pivoted clutch wing can be very easily shifted to the position shown by dot and dash lines (Fig. II) for the purpose of removing the grappling device. If the axis of the pivot 7 was concentric with 25 the center of the circular opening in the plug A, the pivoted wing 8 would not swing toward and away from the inner face of the circular plug, but by locating the pivot eccentrically to the extremities of the clutch 30 wings, or to the center of the plug, the pivoted wing 8 can be moved away from the inner face of the plug, as suggested by arrows in Fig. II.

Shoulders 13, formed on the clutch wings, 35 preferably extend over the upper edge of the plug A (Fig. III), and the top faces of the extended upper portions of the clutch wings are preferably inclined upwardly and inwardly from said shoulders 13, so that the 40 device can be easily pulled through one of the plug-receiving holes 1, shown in Fig. I.

It will now be understood that the grappling device, consisting of a plurality of simple clutch members, may be securely attached to the hollow object by merely holding 45 the pivoted wing 8 in the position shown by dot and dash lines (Fig. II), then inserting the device into the hollow object and thereafter releasing the pivoted wing to al-

50 low the spring 9 to automatically shift the pivoted wing to its locking position, thereby securely interlocking the device with the hollow plug.

After the grappling device has been 55 dropped through one of the openings 1 and interlocked with a tapered plug A (Fig. I), the extended upper portions of the device project from the relatively small end of the plug, and owing to the peculiar manner in 60 which these extended portions are formed, they serve as means for guiding the plug and grappling device into the opening to be closed by the plug, and the plug can be easily inserted by merely pulling the chain 3.

I claim:—

1. In a self-locking expanding grappling device adapted to be inserted into and interlocked with the object to be secured, a pair of rigid sheet metal clutch wings formed integral with each other, pivot-receiving ears projecting from said clutch wings, a pivot pin mounted in said ears, a movable clutch wing mounted on said pivot, the axis of the pivot being eccentric relative to the extremities of 70 the clutch wings so that the pivoted clutch wing may be moved on its axis to allow the device to be secured in and removed from a circular opening, a spring whereby the pivoted clutch member is moved to its interlocking position, said spring being coiled around said pivot, and a stop whereby the pivoted clutch member is stopped in its interlocking position.

2. In a self-locking grappling device for 85 securing objects having tapered openings, a series of clutch wings adapted to be inserted into the tapered openings, an eccentric pivot whereby one of said clutch wings is connected to the others, the pivoted clutch wing 90 being movable on its axis to attach and release the grappling device, and a spring tending to retain said pivoted clutch wing in its attaching position.

3. In a device for inserting hollow tapering 95 boiler plugs into the openings to be closed, a grappling device small enough to be inserted through the openings and dropped into the boiler, said grappling device comprising expanding clutch members coöperable with 100 the tapering inner faces of the hollow plugs, said clutch members having extended upper margins adapted to project from the open ends of the tapering plugs, said upper margins being extended laterally to provide 105 shoulders adapted to overlie the edges of the open ends of the plugs and the top faces of said upper margins being inclined upwardly and inwardly from said shoulders 110 so as to guide the plugs and grappling device into said openings, and a flexible lifting device whereby the grappling device and the tapering plugs are lifted and pulled into said openings.

4. In an expanding grappling device 115 adapted to be inserted into and interlocked with a circular object, a plurality of clutch members one of which is pivoted to the others, the pivoted clutch member being movable on its axis to allow the device to 120 be inserted into and removed from the circular object said axis of the pivot being substantially parallel with the axis of the circular object, and a spring tending to retain said pivoted clutch member in its attaching 125 position.

5. In a self-locking expanding grappling device adapted to be inserted into and interlocked with the object to be secured, a plu-

rality of clutch members, an eccentrically mounted pivot whereby one of said clutch members is supported, the eccentrically pivoted clutch member being movable on its axis to allow the device to be inserted into and removed from a circular opening, the axis of said pivot being approximately parallel with said circular opening, a spring

whereby said pivoted clutch member is moved to its interlocking position, and a stop whereby said pivoted clutch member is stopped in its interlocking position.

In testimony that I claim the foregoing I hereunto affix my signature.

FREDERICK E. KEY.
